Inventor
John W. Brennessel,
By his Attorney, Edgar L. Galt.

UNITED STATES PATENT OFFICE.

JOHN W. BRENNESSEL, OF BROOKLYN, NEW YORK.

DIE-STOCK OILER.

1,147,781.

Specification of Letters Patent. Patented July 27, 1915.

Application filed August 21, 1914. Serial No. 857,820.

To all whom it may concern:

Be it known that I, JOHN W. BRENNESSEL, a citizen of the United States, and residing at Brooklyn, in the county of Queens and 5 State of New York, have invented certain new and useful Improvements in Die-Stock Oilers, of which the following is a specification, such as will enable those skilled in the art to which it appertains to make and use 10 the same.

This invention relates to die stocks, and the object thereof is to provide a device of this class, of the usual construction, with improved means for oiling or lubricating 15 the operative parts, and with this and other objects in view the invention consists in means for oiling a die stock or the operative parts thereof, constructed and operating as hereinafter described and claimed.

20 The invention is fully disclosed in the following specification, of which the accompanying drawing forms a part, in which the separate parts of my improvement are designated by suitable reference characters in 25 each of the views, and in which;—

Figure 1 is a side view of an ordinary die stock provided with my improvements; Fig. 2 a transverse section on the line 2—2 of Fig. 1, and on an enlarged scale; Fig. 3 a 30 transverse section on the line 3—3 of Fig. 2; Fig. 4 a side view of my improved oiling device detached from the stock; and Fig. 5 a perspective view of a bracket plate, which I employ in securing the oiling device to the 35 die stock.

In the accompanying drawing I have shown at *a* an ordinary die stock having end extensions *a*² with which are connected the ordinary handles *a*³, and the stock is provided centrally of the back thereof with a tubular neck *a*⁴ through which the work piece *b* is passed. The stock *a* is also provided centrally of the opposite sides thereof, with apertures *a*⁵ through which the scrap 40 produced by the operation of the die is discharged and in the front of the body of the die are placed the usual die jaws *c*, and all these features are or may be of the usual or any preferred construction.

45 In the practice of my invention I provide a small oil tank *d*, which is rectangular and oblong in form and provided at the bottom with a downwardly and forwardly directed neck *d*² having a forwardly and downwardly directed nozzle *d*³ which is protected, when 50 the device is not in use, by a tubular cap *d*⁴

screwed into the neck *d*² which is threaded as shown at *d*⁵ for this purpose.

The tank *d* is provided centrally of the top thereof with a neck *d*⁶ on which is mounted a tubular cap *d*⁷ having threaded connection with the neck *d*⁶, and the cap *d*⁷ is provided in the top thereof with a conical recess *d*⁸ having a small port *d*⁹, which communicates with the interior thereof and placed in said cap and normally resting on the neck *d*⁶ is a valve *e* which is vertically movable in said cap, and the opposite sides of which are provided with grooves *e*², and said valve is provided in the top thereof with a raised part *e*³ which is adapted to close the port *d*⁹ when the die stock or tool is inverted or turned over.

70 The tank *d* is connected with the die stock by an L-shaped bracket plate *f* provided in the top thereof with a longitudinal slot *f*², and at the bottom thereof with a foot piece *f*³ and a screw *g* which is passed through the foot piece *f*³ into the neck *a*⁴ of the die stock, and the back of the tank *d* is provided centrally of the top thereof with a screw *h* which passes through the slot *f*² in the bracket plate *f* and is provided with a nut *h*², and by means of this construction the tank may be firmly connected with the die 75 stock whenever desired and easily detached therefrom when necessary.

80 The die stock *a* is provided on both sides thereof with a longitudinal flange or rib *a*⁶ against which the front side of the tank *d* abuts when in position, as clearly shown in 85 Fig. 1, and the neck *a*⁴ at the back of the die stock is provided with a collar *i* through which the work piece *b* is passed.

With this construction, when the cap *d*⁴ 90 is detached and the tank *d* secured in place, the oil will automatically flow through the nozzle *d*³ and will be discharged onto or into the operative parts of the die or die stock, as will be readily understood when the die 95 stock is held in the position shown in Figs. 1 and 2, but if the position of the die stock be reversed the flow of oil will immediately stop.

100 The details of the construction *d*⁷ of the oil tank *d*, including the valve *e* are for the purpose of admitting air to the tank *d* so as to permit of the free flow of the oil through the nozzle *d*³, and in filling the tank *d* with oil the cap *d*⁷ with the valve *e* is detached.

105 By means of the slot *f*² in the bracket plate *f*, and the screw *h* with its nut *h*², the tank

d may be adjusted if desired, and within certain limits toward and from the die stock, and my invention does not in any way change the construction of the die stock and 5 may be applied to devices of this class of well known form and construction by simply tapping the back neck *a*⁴ of the die stock to permit the use of the screw *g*, and while I have shown and described the preferred 10 form and construction of my improvement, my invention is not limited to the exact details thereof as herein set out, and changes therein and modifications thereof may be made within the scope of the appended 15 claims, without departing from the spirit of my invention or sacrificing its advantages.

Having fully described my invention, what I claim as new and desire to secure by 20 Letters Patent is:—

1. The herein described oiling device for die stocks comprising a tank provided at the bottom thereof with a discharge nozzle, and at the top thereof with a tubular neck having a detachable tubular cap provided in the top portion thereof with an air port, and a vertically movable valve placed in said cap and adapted to close said port.
2. An oiling device for die stocks comprising a tank provided at the bottom there-

of with a discharge nozzle, and at the top thereof with a detachable cap having an air port, a valve within said cap and which controls said port, and a bracket device adapted to be secured to the die stock and with which 35 the tank is adapted to be connected.

3. An oiling device for die stocks, comprising a tank provided at the bottom thereof with a discharge nozzle and at the top thereof with a cap having in the top portion 40 thereof an air port, and a valve placed in said cap and which opens inwardly and closes outwardly.

4. An oiling device for die stocks, comprising a tank provided at the bottom thereof with a discharge nozzle and at the top thereof with a cap having in the top portion 45 thereof an air port, and a valve placed in said cap and which opens inwardly and closes outwardly, said discharge nozzle being also provided with a detachable cap.

In testimony that I claim the foregoing as my invention I have signed my name in presence of the subscribing witnesses this 20th day of August 1914.

JOHN W. BRENNESSEL.
